(57) **CLAIM**

The athletic shoe tongue sleeve, as shown and described.

DESCRIPTION

FIG. 1 is a front view of the athletic shoe tongue sleeve.

FIG. 2 is a back view thereof.

FIG. 3 is a top view (as seen from the front view) thereof.

FIG. 4 is a bottom view (as seen from the front view) thereof.

FIG. 5 is a left side view thereof.

FIG. 6 is a right side view thereof; and,

FIG. 7 is a perspective view thereof.

Broken lines are used in the drawings to show the environment related to the claimed design. Each of the lighter broken lines shown in FIGS. 1, 2, 5, 6 and 7 are for the purpose of showing the stitching only. Each of the darker broken lines shown in FIGS. 1 and 7 are for the purpose of showing openings. The broken lines form no part of the claimed design.
